DESIGN FOR AN ALPHABET AND NUMERAL CUT-OUT SHEET

Charles Hensel, New York, N. Y.

Application April 17, 1937, Serial No. 68,848

Term of patent 14 years

To all whom it may concern:

Be it known that I, Charles Hensel, a citizen of the United States, residing at New York, in the county of New York, and State of New York, have invented a new, original, and ornamental Design for Alphabet and Numeral Cut-Out Sheet, of which the following is a specification, reference being had to the accompanying drawing, forming part thereof.

Figure 1 is a front view of the alphabet and

numeral cut-out sheet showing my new design;

Figure 2 is a vertical sectional view taken on line 2—2 of Figure 1; and

Figure 3 is a horizontal sectional view taken on line 3—3 of Figure 1.

I claim:

The ornamental design for an alphabet and numeral cut-out sheet, as shown.

CHARLES HENSEL.
